UNITED STATES PATENT OFFICE

113,410

DESIGN FOR A HANDLE FOR CHAFING DISHES, TOASTERS, AND THE LIKE

Walter von Nessen, New York, N. Y., assignor to Chase Brass & Copper Co., Incorporated, Waterbury, Conn., a corporation of Connecticut

Application November 15, 1937, Serial No. 72,899

Term of patent 14 years

To all whom it may concern:

Be it known that I, Walter von Nessen, a citizen of the United States, residing at New York, in the county of New York and State of New York, have invented a new, original, and ornamental Design for a Handle for Chafing Dishes, Toasters, and the like, of which the following is a specification, reference being had to the accompanying drawing, forming part thereof.

Fig. 1 is a perspective view of a handle for chafing dishes, toasters, and the like, showing my new design;

Fig. 2 is a top plan view thereof;

Fig. 3 is a face view thereof; and
Fig. 4 is an edge view thereof.

The design is characterized by its U-shaped form in cross-section and a series of ridges or flutes extending transversely of the handle.

The handle is also adapted to be used on articles of furniture such as dresser drawers or the like.

I claim:

The ornamental design for a handle for chafing dishes, toasters, and the like, substantially as shown and described.

WALTER VON NESSEN.
